AMPLITUDE FILTER

Kurt Schlesinger, Berlin, Germany, assignor, by
mesne assignments, to Loewe Radio, Inc., a cor-
poration of New York

Application April 24, 1935, Serial No. 17,960
In Germany April 28, 1934

2 Claims. (Cl. 178—7.3)

The subject matter of the present invention is a valve circuit, which solves the problem of extracting from a signal comprising impulses of different amplitudes, those impulses whose amplitudes exceed a certain threshold value, and withholding all impulses whose amplitudes are less than this value. The circuit according to the invention also solves the problem, in the case of amplification of this signal, in which the relative amplitudes of the impulses remain unaltered, whilst the absolute values are greatly varied, of shifting the threshold value so that, as before, only the extreme peaks of the signal pass the filter, whilst the amplified signals of lower amplitudes, as before, are withheld.

For this purpose, according to the invention, there are provided in the circuit means which cause the separating value of the mixture to be varied corresponding with the variations in the total amplification.

These means may be constructed as automatically acting or also as manually controlled means.

The arrangement according to the invention is of particular importance as regards television receivers, which are to be synchronised from the transmitter and makes use of a three-electrode valve in connection with a grid leak resistance with a parallel connected capacity.

The method according to the invention is described in conjunction with the drawing, where in:

Figure 1 shows one form of the present invention and

Figure 2 shows comparative signaling strengths of the detected signals.

From a receiving rectifier 1, in Fig. 1, for example a push-pull detector, the image current passes over a line 2 through the medium of a condenser 3 to the Braun tube 4. The line 2 is accordingly traversed by image potentials of the order of, for example, approximately ± 10 volts.

In Fig. 2 the amplitude values for strong and weak reception are shown the values for weak reception being shaded or hatched. Thus, for example, for a strong received signal the extreme white is entered with $+10$ volts, and the extreme black with -10 volts. With a ratio as 3:2 between the amplitudes of synchronisation impulses and maximum image currents the peaks of the synchronizing impulses 5 in Fig. 2 then have an amplitude of -15 volts.

The shaded values apply to weak reception. They are given as ± 3 volts for the image and -4 volts for the synchronisation signals. The object of the circuit according to the invention

consists in performing an amplitude filtering for example at either of the values -12 or -3.5 , and in allowing all impulses to pass which are more negative than the stated value and withholding the remainder. The desired limits are shown in dash-dotted lines in Fig. 2 and are designated 6 and 6' respectively.

The problem is solved according to the invention for example by a single-grid tube 7 in Fig. 1 in the following manner: The cathode of the tube 7 is connected through a resistance 8 of approximately 0.1 megohm with a positive potential of 3.5 volts as compared with the grid 9 of the same tube. At the same time it is connected with the line 2 traversed by the image current 15 through a condenser 3' of approximately 0.005 mf, which blocks the passage of low frequencies, but allows the passage of the short and long synchronisation impulses to an equal degree. The potential of the anode battery 10 is selected to be such that the anode current only commences when the potential cathode and grid exceeds the blocking value of 3.5 volts. It is clear that immediately the cathode receives negative impulses greater than this magnitude from the image current line 2, the extent of which exceeds the stated value, corresponding current impulses will occur in the anode circuit. These current impulses have in themselves a negative sign; they should, therefore, as already set forth by the applicant on a previous occasion, preferably be reversed in their phase by means of two flatly tuned transformers 11 and 12. The transformer 11 is tuned to the frequency of the short and the transformer 12 to the frequency of the long synchronizing signals. With the terminals 13 or 14 there may then be directly connected the control grids of the relaxation oscillators, which preferably contain a gas discharge tube.

If the signals in the line 2 become stronger owing to a higher degree of amplification by the receiver or by increase in the intensity of the receiving field or the like, there would be, if special precautions were not taken, not only an over-control of the relaxation apparatus but also interference in the synchronism owing to the fact that not only do the synchronizing impulses exceed the cut off level but also the amplified black portions of the image signal. The problem of increasing the cut off level 6' in Fig. 2 to a correspondingly greater value 6, i. e., for example from 3.5 to 12 volts, is solved according to the invention by utilising the grid current in the tube 7. For this purpose the grid is earthed through a condenser 15 and a parallel resistance 16. The

condenser 15 is selected to be so small that it short-circuits the high frequencies, but on the other hand it may be charged in a comparatively short time by the grid current (a suitable value is e. g., approximately 100 mmf.). If the leak resistance 16 were missing, the grid, therefore, would apparently be charged to the highest negative peak value occurring. A control effect in the anode circuit would, therefore, cease altogether. By reason now of the leak resistance 16 the grid is charged not to the peak value of the maximum negative potential, but to a value that is always less negative to a certain extent. In consequence only the extreme peaks of the impulses—and only these—appear in the anode current. The resistance 16 is so selected that the condenser 15 is only capable of again being charged after termination of a relatively large group of lines, and not between every line. The same, therefore, in view of the small value 15, must have an appreciably high value of several megohms. As a result only very small amounts of current are necessary for maintaining the bias value of the grid once it is adjusted.

25 The problem of subsequently regulating the amplitude sensation level in accordance with the output potential in the line 2 may be solved not only in the stated manner, but also in other fashion.

30 It is possible, for example, according to a modification of the invention, to obtain the bias for the grid of the tube 7 from a potentiometer, and couple this potentiometer mechanically with the amplification control, so that the bias is adjusted

35 so that the synchronizing signal is separated even with the weakest reception. The bias then becomes more negative when stronger signals are received and the separation level is changed to effect the desired results.

40 According to the invention, there is also the possibility of conducting a part of all of the bias of the grid 9, over a line 17 and a high-pass filter consisting of the resistance 18 and the condenser 19 to the control grids of one or more receiving

45 amplifier valves of the television receiver so that the output potential of the line 2 is maintained constant automatically.

The method which has been described above for upwardly modulated television transmitters 50 and negatively poled synchronizing signals may be employed also for other kinds of modulation. For example transmissions with positively poled impulse peaks may also be received by interchanging the cathode and grid connections, i. e., 55 the condenser 3' is connected with the grid 9 instead of with the cathode.

In the case of possible capacitative coupling of the grid circuit and anode circuit there may also be introduced in obvious fashion a screen grid. 60 An important advantage may be obtained by utilizing the curvature of the characteristic of the amplifier to obtain a considerable increase in the amplification of the synchronizing signals as compared with the image current signals, so that 65 danger of interference with the synchronizing by peaks in the image current is lessened to a considerable extent.

I claim:

1. A television receiver wherein picture and 70 synchronizing signals are received as a modulation of a common carrier frequency and wherein the synchronizing signals have a greater amplitude than any picture signals, means for amplifying the modulated carrier frequency, a demodulator tube having input and output electrodes,

means for applying the modulated carrier to the input electrode of the demodulator tube whereby detected picture and synchronizing signals are present at the output electrode of said tube with the synchronizing signals extending in a negative direction, a separator tube including a cathode, a control electrode and an output electrode, a source of potential, means including a parallel connected condenser and resistance combination for connecting the control electrode of said separator tube to the negative terminal of the source of potential, means including a load circuit for connecting the output electrode of said separator tube to the positive terminal of the source of potential, means including an impedance for normally maintaining a positive bias on the cathode relative to the control electrode by a predetermined amount, means including a condenser for connecting the cathode of said separator tube to the output electrode of said demodulator tube to vary the potential of said cathode in accordance with variations in amplitude and voltage of the detected picture and synchronizing signals from a predetermined normal amplitude and voltage value, said resistance and condenser combination 25 being adapted to alter the bias voltage applied to the control electrode of the separator tube in a negative direction in accordance with increases in the signal strength of the detected synchronizing signals, whereby said separator tube is rendered conductive only upon the presence of synchronizing signals irrespective of the variations in the amplitude and voltage of the detected signals, and conductive means for coupling the control electrode of the separator tube to the means for 30 amplifying the modulated carrier frequency to vary the amplification level thereof.

2. A television receiver wherein picture and synchronizing signals are received as a modulation of a common carrier frequency and wherein the synchronizing signals have a greater amplitude than any picture signals, means for amplifying the modulated carrier frequency, a demodulator tube having input and output electrodes, means for applying the modulated carrier to the input electrode of the demodulator tube whereby detected picture and synchronizing signals are present at the output electrode of said tube with the synchronizing signals extending in a negative direction, a separator tube including a cathode, a control electrode and an output electrode, a source of potential, means including a parallel connected condenser and resistance combination for connecting the control electrode of said separator tube to the negative terminal of the source of potential, means including a load circuit for connecting the output electrode of said separator tube to the positive terminal of the source of potential, means including an impedance for normally maintaining a positive bias on the cathode relative to the control electrode by a predetermined amount, means including a condenser for connecting the cathode of said separator tube to the output electrode of said demodulator to vary the potential of said cathode in accordance with variations in amplitude and voltage of the detected picture and synchronizing signals from a predetermined normal amplitude and voltage value, said resistance and condenser combination being adapted to alter the bias voltage applied to the control electrode of the separator tube in a negative direction in accordance with increases in the signal strength of the detected synchronizing signals, whereby said separator tube is rendered conductive only upon the presence of syn- 75

chronizing signals irrespective of the variations in the amplitude and voltage of the detected signals, the time constant of said condenser and resistor combination corresponding to the time

5 interval occupied by several successive synchronizing signals, and conductive means for cou-

pling the control electrode of the separator tube to the means for amplifying the modulated carrier frequency to vary the amplification level thereof.
